UNITED STATES PATENT OFFICE.

JAMES FREDERICK THOMAS, OF PHILADELPHIA, PENNSYLVANIA, ASSIGNOR
TO JAMES E. CALDWELL & CO., OF SAME PLACE.

DESIGN FOR A SPOON.

SPECIFICATION forming part of Design No. 20,987, dated August 11, 1891.

Application filed July 2, 1891. Serial No. 398,316. Term of patent 3½ years.

To all whom it may concern:

Be it known that I, JAMES FREDERICK THOMAS, a citizen of the United States, and a resident of the city and county of Philadelphia, and State of Pennsylvania, have invented and produced a new and original Design for Spoons, of which the following is a specification, reference being had to the accompanying photographs, forming part 10 thereof.

Figure 1 is a front elevation of my newly designed spoon, and Fig. 2 a rear elevation.

The handle of my spoon consists of a representation of William Penn A, standing upon a keystone B, upon the front of which is a scroll C, upon which the word "Philadelphia" is traced. This word may be entirely omitted, as it does not form a part of

my design. Upon the rear of the keystone is scroll-work, substantially as shown. Upon the interior of the bowl of the spoon is a perspective view of the Philadelphia City Hall. The figure of William Penn is represented in the conventional manner. He is clothed in a long coat, knee-breeches, and a broad-brimmed hat. His hair is long. His right hand is slightly raised, and in his left hand he holds a partly-unrolled scroll.

Having thus described my invention, I claim—

The design for a spoon, as herein shown and described.

JAMES FREDERICK THOMAS.
